UNITED STATES PATENT OFFICE.

RAYMOND K. WHITNEY, OF MANHATTAN, KANSAS.

DESIGN FOR A TOY VEHICLE.

54,227.

Specification for Design.

Patented Nov. 18, 1919.

Application filed September 2, 1919. Serial No. 321,284. Term of patent 14 years.

To all whom it may concern:

Be it known that I, RAYMOND K. WHITNEY, a citizen of the United States, residing at Manhattan, in the county of Riley and the State of Kansas, have invented a new, original, and ornamental Design for a Toy Vehicle, of which the following is a specification, reference being had to the accompanying drawing, forming part thereof.

The figure is a perspective view of a toy vehicle, showing my new design.

I claim:

The ornamental design for a toy vehicle as shown.

RAYMOND K. WHITNEY.
